UNITED STATES PATENT OFFICE

PAUL M. WILCOX, OF LA PORTE, INDIANA, ASSIGNOR TO WILCOX DRAIN CORPORATION,
OF LA PORTE, INDIANA, A CORPORATION OF INDIANA

ROOF DRAIN

Application filed January 7, 1931. Serial No. 507,110.

My invention relates to improvements in roof drains and has for one object to provide a new and improved form of roof drain with a positive rigid and secure clamping of the roofing fabric. Another object is to provide a device wherein the clamping posts are fully protected from weather and traffic, to provide a dome strainer which cannot be blown or knocked over, to provide a body design which eliminates the possibility of air pockets, which is in itself self-cleaning, wherein the clamping means and the strainer are to a maximum extent free from rusting or freezing in place. Another object is to provide a clamping device for the roofing fabric which will protect the fabric at points of greatest weakness where it is attached to the drain and wherein the only aperture or perforation through the fabric is the single hole necessary to permit registering and positioning of the fabric about the drain.

My invention is illustrated more or less diagrammatically in the accompanying drawings, wherein—

Figure 1 is a vertical section;

Figure 2 is a plan view with parts in section;

Figure 3 is a section along the line 3—3 of Figure 2;

Figure 4 is a vertical section through a slightly modified form.

Like parts are indicated by like characters throughout the specification and drawings.

A is a funnel terminating in a downwardly extended threaded sleeve A¹ into which is threaded a drain pipe A². The funnel is generally conical in shape being made up of a cylindrical section A³ with a lower conical section A⁴ between it and the sleeve A¹, an upper conical section A⁵, an annular section A⁶, a conical mouth section A⁷ and a peripheral flange A⁸; between the cylindrical section A³ and the conical section A⁵ is an annular section A¹⁵.

Cast integral with the funnel are a plurality of clamping posts or lugs B projecting upwardly from the annular portion of the funnel A⁷ to a point above the flange A⁸,

these lugs being spaced inside the inner periphery of the funnel. These lug castings extend downwardly outside the funnel below the annular portion A¹⁵ alongside of the cylindrical portion A³ as indicated at B¹. 55 The outer side of each lug at a point above the flange A⁸ is provided with a dove-tail pocket B² which pocket is engaged by the dove-tail on a clamp block B³, the clamp block being free to be displaced laterally but held against longitudinal movement by its dove-tail relation with the lug. B⁴ is a clamping screw threaded in the block B³ extending downwardly to engage a clamping ring B⁵ which clamping ring extends about 60 the entire periphery of the funnel and is of such shape as to rest upon the annular portion A⁶ and to be in general parallelism with the conical portion A⁷. This ring has a flange B⁶ which extends upwardly about its 65 outer periphery and is so arranged that this flange is at right angles to the annular lip or ring A⁸ and is immediately above the inner periphery thereof. The screw is provided with a head B⁷ above the block B³. 75 The inner periphery of the clamping ring B⁵ is notched to interlock with the clamping lugs or posts B. B⁸ is the roof fabric or packing means. There is of course a hole cut in it where it registers with the roof drain 80 and the material at the periphery of that hole rests on the flange A⁸, is held between the clamp B⁵ and the mouth of the drain being first bent downwardly into parallelism with the conical portion A⁷ and then into horizontal position in parallelism with the annular portion A⁶ and then again into parallelism with the conical portion A⁵ by the contour of the clamping ring. Thus there 85 are three bends in this fabric so as to make a tight joint and since the clamping ring is seated from above, there are no additional holes through the fabric to permit leakage. The flange B⁶ projecting upwardly from the clamping ring immediately above the place 90 where the fabric is bent downwardly for the first time protects this bent portion of the fabric. Since this bent portion is exposed in part at least beyond the clamping ring, 95 that is a point of weakness and the upstand- 100

ing flange protects that point of weakness against traffic and against abrasion when the device is used with a tar and gravel roof and the fabric is in part at least a wearing surface. The upper surface of the clamping ring is provided in line with each of the clamping posts with a shallow pocket B^6 to engage the end of the locking screw to prevent drifting of the screw as it is tightened up and steady and support the free end of the screw. The flange B^6 is interrupted by a series of notches about its periphery between the clamping posts so that this flange will not prevent drainage across the roofing fabric. These notches are narrow enough so as not to interfere with the protecting function of the flange B^6 and narrow enough to limit the size of particles which pass through so as to prevent gravel and roofing particles being washed down the drain.

The dome strainer C penetrates into the mouth of the funnel and projects above the clamping lugs or posts. This dome strainer is preferably made in a casting and rests on pads C^1 projecting upwardly from the annular surface A^{15} on either side of each of the clamping posts. These pads serve the two-fold function of supporting the strainer and reinforcing the funnel casting at the point where the clamping posts project from it. The presence of these pads lifts the lower rim of the strainer out of contact with the annular surface A^{15} so that there is opportunity for free water passage between this surface and the strainer and the only contact between the strainer and the funnel is the contact along horizontal lines between the underside of the strainer and these pads, thus minimizing the danger of rusting or freezing in place. Projecting laterally from the strainer and integral therewith are a plurality of pockets C^2 , these pockets being enclosed on three sides as indicated at C^3 and cut away toward the bottom adjacent the funnel so as to enclose the upper ends of the clamping posts, clamp blocks and the clamping screws thereby preventing them from being disturbed by traffic; protecting them against the weather and the parallel sides of the pockets are so related to the clamping elements that in order to disengage the strainer from the funnel the strainer must be raised upwardly a distance substantially equal to the height of the lug before it may be removed. This makes a structure which cannot be blown or knocked off accidentally because a sidewise pressure which might tend to tilt the strainer would jam it in position long before the strainer would be lifted out of register with the funnel and the clamping means.

It will be evident that while I have shown in my drawings an operative device, still many changes might be made in the size,

shape, arrangement, number and disposition of parts without departing materially from the spirit of my invention and I wish, therefore, that my showing be regarded as in a sense diagrammatic.

Referring to the modified form shown in Figure 4, D is a clamp ring. It is different from the clamp ring B^5 of the form shown in Figure 3 in that it does not have the notches for the inward flow of water. It extends up toward the surface of the floor which in this case is considerably above the locking means, since this device is intended for floors rather than roofs. D^1 is a flange corresponding to the flange B^6 , it extends up to provide a form for the concrete floor. D^2 are drain holes to provide for any leakage beneath the floor. They are substituted for the notches B^6 . D^3 is a rabbeted ring resting on top of the flange D^1 secured in place by screws D^5 in lugs D^4 . D^6 is a flat surfaced grate which as a substitute for the dome, fits into the rabbeted depression in the ring D^3 . In this application of my invention the holding lugs, the removable clamp members and the screws are all contained beneath the floor surface and their only protection comes from the fact that the flat surfaced grate is apertured only out of line with them.

I claim:

1. In a roof drain, a funnel, a clamp ring adapted to penetrate within the mouth thereof, and notched upon its inner periphery, holding lugs projecting upwardly from the inner wall of the funnel and adapted to engage the notches in the clamp ring.

2. In a roof drain, a funnel, a plurality of holding lugs projecting upwardly from the inner wall and inside the mouth thereof, a clamping ring located between the lugs and the outer periphery of the funnel adapted to penetrate the mouth thereof, and means interposed between the lugs and the clamping ring and located above the mouth of the funnel for holding the clamping ring in position, said means comprising clamping blocks removably dove-tailed in the lugs and clamping screws threaded in the blocks adapted to engage the clamping ring.

3. In a roof drain, a funnel, a plurality of holding lugs projecting upwardly from the inner wall and inside the mouth thereof, a clamping ring located between the lugs and the outer periphery of the funnel adapted to penetrate the mouth thereof, and means interposed between the lugs and the clamping ring and located above the mouth of the funnel for holding the clamping ring in position, said means comprising clamping blocks removably dove-tailed in the lugs and clamping screws threaded in the blocks adapted to engage the clamping ring, the clamping ring having an outer peripheral flange projecting

upwardly outside of the blocks to protect the screws.

4. In a roof drain, a funnel, a plurality of holding lugs projecting upwardly from the inner wall and inside the mouth thereof, a clamping ring located between the lugs and the outer periphery of the funnel adapted to penetrate the mouth thereof, and means interposed between the lugs and the clamping ring and located above the mouth of the funnel for holding the clamping ring in position, said means comprising clamping blocks removably dove-tailed in the lugs and clamping screws threaded in the blocks adapted to engage the clamping ring, the clamping ring having an outer peripheral flange projecting upwardly outside of the blocks to protect the screws, and removable means associated with the funnel overlying the blocks, lugs and screws and extending downwardly toward the flange on the clamping ring to enclose the clamping means.

5. In a roof drain, a funnel, a plurality of holding lugs projecting upwardly from the inner wall and inside the mouth thereof, a clamping ring located between the lugs and the outer periphery of the funnel adapted to penetrate the mouth thereof, and means interposed between the lugs and the clamping ring and located above the mouth of the funnel for holding the clamping ring in position, said means comprising clamping blocks removably dove-tailed in the lugs and clamping screws threaded in the blocks adapted to engage the clamping ring, the clamping ring having an outer peripheral flange projecting upwardly outside of the blocks to protect the screws, and removable means associated with the funnel overlying the blocks, lugs and

screws and extending downwardly toward the flange on the clamping ring to enclose the clamping means and a strainer penetrating the mouth of the funnel and integral with said clamp enclosing means.

6. Clamping means for roof drains and the like comprising in combination with a roof drain funnel, an integral lug projecting upwardly from the inner wall, at a point spaced inwardly from the outer periphery thereof, a clamping member adapted to lie in general parallelism with the inner surface of the funnel, a block removably dove-tailed in the lug and a screw threaded in the block adapted to exert a downward pressure upon the clamping means to seat it in the mouth of the funnel.

7. A roof drain comprising a funnel, a plurality of lugs, projecting upwardly from the wall thereof and inside the mouth thereof, packing clamping means associated with the funnel and supported on said lugs, a strainer closing the mouth of the funnel and having integral closed pockets projecting therefrom and engaging the lugs enclosing the clamping means.

8. A roof drain comprising a funnel, a plurality of lugs projecting upwardly from the wall thereof and inside the mouth thereof, packing clamping means associated with the funnel and supported on said lugs, a strainer closing the mouth of the funnel and having integral closed pockets projecting therefrom and engaging the lugs enclosing the clamping means, the walls of said pockets being substantially parallel with the lugs to compel relatively extended upward movement of the strainer before it can be disengaged from the funnel.
